(57) **CLAIM**

The ornamental design for a base of a dial based closure device as shown and described.

DESCRIPTION

1. Base of a dial based closure device

1.1 : Perspective

1.2 : Front

1.3 : Back

1.4 : Right

1.5 : Left

1.6 : Top

1.7 : Bottom

The base is attachable to an article, such as an article of footwear; a dial based closure device can be removably attached to the base to attach the dial based closure device to the article; the portions illustrated by solid lines are the portions for which the claimed design is intended; the broken lines in the drawings represent environment that form no part of the claim.
